CLAIM

(21) Appl. No.: **29/139,738**

The ornamental design for an interior illuminated lamp in the shape of a shark, as shown and described.

(22) Filed: **Apr. 6, 2001**

DESCRIPTION

(51) LOC (7) Cl. **26-03**

FIG. 1 is a view in perspective of the present invention;

(52) U.S. Cl. **D26/98**

FIG. 2 is a right side view of the present invention;

(58) Field of Search D26/4, 32, 93-112,

FIG. 3 is a left side view of the present invention;

D26/125, 146, 147, 156; 362/410-414,

FIG. 4 is a front view of the present invention;

806, 808; 446/153, 226, 485; D21/415,

FIG. 5 is a back view of the present invention;

438-440, 576, 584, 597, 599; D11/158

FIG. 6 is a top view of the present invention; and,

(56) **References Cited**

FIG. 7 is a bottom view of the present invention.
